DESIGN FOR A BOTTLE OR SIMILAR ARTICLE

Joseph S. Stein, Chicago, Ill., assignor to Lucien Lelong, Inc., Chicago, Ill., a corporation of Illinois

Application December 5, 1934, Serial No. 54,283

Term of patent 7 years

To all whom it may concern:

Be it known that I, Joseph S. Stein, a citizen of the United States, and a resident of the city of Chicago, county of Cook, and State of Illinois, have invented a new, original, and ornamental Design for a Bottle or Similar Article, of which the following is a specification, reference being had to the accompanying drawing, forming a part thereof.

On the drawing:

Figure 1 is a perspective view of the bottle or similar article.

Figure 2 is a front elevation thereof.

I claim:

The ornamental design for a bottle or similar article, as shown.

JOSEPH S. STEIN.
